John T. Raper
INVENTOR
BY Victor J. Evans

ATTORNEY

WITNESS: J. T. L. Wright

UNITED STATES PATENT OFFICE.

JOHN T. RAPER, OF LUCAMA, NORTH CAROLINA.

NEEDLE.

Application filed December 30, 1925. Serial No. 73,484.

This invention relates to a needle, the general object of the invention being to provide means whereby the needle can be easily threaded by forming a cut in the same which extends from the eye through one side of the needle.

Another object of the invention is to provide the needle with a resilient part which permits the cut part to be separated, for 10 the entrance of the thread, after which the parts are returned to normal position to hold the thread in the eye and prevent the needle from catching in the material.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:—

Figure 1 is an elevation of the improved needle.

Figure 2 is a section on line 2—2 of Figure 1.

Figure 3 is a section on line 3—3 of Figure 1.

As shown in these views, the needle 5 is formed with two parallel cuts 6 and 7 and a cross cut 8 which form a tongue 9 in the central part of the needle. The free end of this tongue is cut off so as to provide an eye 10 for receiving the thread. The cut 7 is of greater length than the cut 6, and said cut 7 forms a spring part 11 which permits bending of the pointed part of the needle so that the walls of the cut 6 can be separated, this cut extending through one side

of the needle, as shown at 6'. Thus thread can be passed through the cut 6 until it enters the eye 10, so that the needle can be 45 threaded very easily and by a person with poor eyesight, as it is not necessary to pass the thread through a small eye, as in needles now on the market. The walls of the outer end of the cut 6' are rounded, as shown, to 50 prevent these portions from hanging in the cloth being sewed.

With this needle, it is simply necessary to draw the thread through the cut 6 and 6' into the eye, the spring part 11 permitting 55 the parts to separate sufficiently to permit the thread to pass. The needle is also provided with opposing grooves 12 which extend longitudinally of the needle and increases the resiliency of the part 11 as it 60 weakens that part of the needle at the junction of the part 11 with the body of the needle. The grooves reduce the thickness of the tongue 9.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A needle having a pair of parallel cuts in its body which extend longitudinally of the 75 body with a cross cut connecting the parallel cuts together, said cuts forming a tongue, the end of which is cut off to form an eye, a notch in one side of the needle communicating with one of the cuts and 80 oppositely arranged grooves in the needle which reduce the thickness of the tongue.

In testimony whereof I affix my signature.
JOHN T. RAPER.
